UNITED STATES PATENT OFFICE

141,361

DESIGN FOR A COMBINATION CLOTHES-BASKET AND BATHINETTE

Jacob A. Deerwester, Minneapolis, Minn.

Application September 20, 1944, Serial No. 115,369

Term of patent 14 years

(Cl. D4—4)

To all whom it may concern:

Be it known that I, Jacob A. Deerwester, a citizen of the United States, residing at Minneapolis, in the county of Hennepin and State of Minnesota, have invented a new, original, and ornamental Design for a Combination Clothesbasket and Bathinette, of which the following is a specification, reference being had to the accompanying drawings, forming part thereof.

I claim:

The ornamental design for a combination clothesbasket and bathinette, as shown.
JACOB A. DEERWESTER.

Certificate of Correction

Design No. 141,361.

May 29, 1945.

JACOB A. DEERWESTER

It is hereby certified that errors appear in the above numbered patent requiring correction as follows: In the grant, line 6, for "BATHINETTE" read BABY BATH; in the heading to the drawings, sheets 1 and 2, line 2, for the words "CLOTHES BASKET AND BATHINETTE" read CLOTHESBASKET AND BABY BATH; in the heading to the printed specification, line 2, for "BATHINETTE" read BABY BATH; in the specification, column 1, line 6, for "Bathinette" read Baby Bath; second column, lines 2 and 8, for "bathinette" read baby bath; and that the said Letters Patent should be read with these corrections therein.

Signed and sealed this 7th day of October, A. D. 1947.

[~~SEAL~~]

THOMAS F. MURPHY,
Assistant Commissioner of Patents.
